UNITED STATES PATENT OFFICE.

SHUBAEL COTTLE, OF NEW YORK, N. Y.

IMPROVEMENT IN DEVICES FOR MANUFACTURING JEWELRY-BASES.

Specification forming part of Letters Patent No. **140,616**, dated July 8, 1873; application filed March 22, 1873.

To all whom it may concern:

Be it known that I, SHUBAEL COTTLE, of the city, county, and State of New York, have invented a new and useful Improvement in Means for Making certain forms of Jewelry-Bases for Studs, Buttons, Settings, Bracelets, Scarf-Rings, &c., of which the following is a specification:

The invention consists in a peculiarly-constructed former combined with a die-burnisher and mandrel, as hereinafter described.

Figure 1 is a plan and section of the blank to be operated upon. Fig. 2 is a plan and section of the former, shown in the blank A. Fig. 3 is a face view and section of the female die. Fig. 4 is a face view and section of the plunger. Fig. 5 is a plan view and section of the blank and former as they come from the die. Fig. 6 is a face view and section of the mandrel. Fig. 7 is a side and edge view of the burnisher. Fig. 8 is a plan and section of the blank as it comes from the mandrel and burnisher. Fig. 9 is a plan view and section of the completed blank.

A represents a blank, having the bottom a and barrel a^1 at a sharp angle, a^2 , to each other. B is a former, made in sections, preferably in five pieces, $b b' b' b' b'$. C is a female die, made with a detachable bottom, C^1 , for convenience in removing the blank, and with a shoulder, C^2 , in its cavity, leaving a space, C^3 , around the barrel a^1 of the blank A when said blank is inserted in said die C. D is a plunger, which is made with a square

edge, d^1 , and a recess, d^2 , having a rounded angle, d^3 .

The former B is placed in the blank A, and the blank is inserted within the shoulder C^2 of the die C. The plunger D is then brought down upon the edge a^3 of the barrel a^1 of the blank A, turning the said edge a^3 inward over the former B, producing the blank A¹.

E is a mandrel, which is made hollow, and with a cavity, e , in which the blank A¹ is placed.

The blank A¹ is now placed in the mandrel E, and while the mandrel is being rotated in a lathe, a burnisher, F, is held against the turned-over edge a^3 , which is thus pressed down upon the former B until it has a sharp angle. This produces the blank A². The blank is now taken out of the mandrel, and the middle section b of the former is removed, and subsequently the others, after which the bottom a is cut out so as to produce the blank A³, which consists of three curved strips, two being horizontal, and the other, which connects them, vertical.

Having thus described my invention, I claim as new and desire to secure by Letters Patent—

The former B, consisting of a middle section, b , and several surrounding sections b' , in combination with a die C D, burnisher F, and mandrel E, as and for the purpose described.

Witnesses: SHUBAEL COTTLE.
